ELECTRIC SWITCH

John S. Nunes, New York, N. Y., assignor to Elizabeth Lefkowitz, doing business as Fulton Electric Mfg. Co., New York, N. Y.

Application January 7, 1941, Serial No. 373,393

3 Claims. (Cl. 200—64)

The present invention relates to electric switches of the hand-operated type, and in particular to switches of the pull-chain type, although the invention is not limited thereto.

It is the general object of the invention to provide an electric switch of inexpensive, compact and durable construction requiring few parts and capable of easy assembly, and which can be readily adapted for use for the control either of single or of multi-circuit installations in homes, stores, industrial establishments, etc.

More particularly, it is an object of the invention to provide a switch of the type indicated which can be readily adapted for the control of additional circuits by the coupling therewith of compact switch units of similar construction.

It is also an object of the invention to provide a switch mechanism having a mounting member upon which can be attached, upon both sides thereof, switch units of the same or of different type and upon which additional units may be mounted in coaxial relation for the control of additional circuits, and all operated by one and the same actuating mechanism.

It is also an object of the invention to provide an improved switch of the rotary type having a plurality of bridging contact-carrying discs mounted upon a common shaft, and particularly a switch of this kind wherein one or more of the discs oscillate through a more or less fixed angle to effect closing and opening of a circuit during a single actuation of the switch, whereby the time during which any particular circuit or circuits remain closed (or open) may be manually controlled, while other circuits connected to the switch are controlled in the usual fashion, that is, are closed and opened only on successive actuations of the switch.

One form of apparatus for which switches of the just mentioned construction are particularly suited is the now well-known fluorescent lamp. In the control of fluorescent lamps, it is now the general practice to provide such lamps with a thermally controlled "starter" which, upon closing of the lamp switch, controls the pre-heating of the lamp and which, after a more or less fixed time interval, automatically breaks the starting circuit and leaves the lamp to be operated by the operating circuit which includes the column of heated or ionized gas between the electrodes inside the lamp. This thermostatically operated starter or switch has proved to be rather unreliable and hence unsatisfactory in operation because of flickering of the lamp apparently caused by insufficient pre-heating of the gas, so that frequently the switch must be closed a second and

even a third time before steady operation of the lamp is obtained. Also, frequent replacement of the starter is usually necessary.

It is accordingly a further object of the invention to provide a switch of the manually-operated type which is adapted to include, as one of the switch units thereof, a hand controlled switch assembly acting to replace the automatic "starter" heretofore employed with fluorescent lamps and similar apparatus, and through which sufficient pre-heating of the gas in the lamps (or other preliminary regulation of other apparatus) may be insured by the operator before the starting circuit is broken.

Another object of the invention is to provide a switch mechanism manually controlled to time the operation of any circuit without requiring the frequent replacement common in known thermal switches, and at the same time eliminating the special ceramic support for such known switches.

It is a still further object of the invention to provide a switch mechanism composed of a plurality of more or less separate switch units, each with its own housing or housing section, which are capable of standardization and of being quickly assembled in numerous combinations to control a great variety of circuits singly and in combination, whereby a minimum of parts and assembled switches need be kept on hand by the manufacturer for prompt filling of orders calling for many different combinations of multi-circuit control.

Other objects of the invention are to provide improved mechanism for actuating a rotary switch; to construct a switch controlling a plurality of circuits in such manner that the cost of wiring is considerably reduced; to provide a switch composed of individual units capable of being assembled into a composite switch capable of controlling two or more electrically operated devices connected in any desired circuit, as in the form of two-way, three-way, and four-way switches, single pole, multi-pole, etc., and in various combinations; to provide a timing switch which can be used equally well in A. C. and D. C. circuits in contrast to the thermal switch which is suitable for A. C. operation only; and to provide an improved form of rotary bridge member which insures against accidental breaking of circuits.

Still other objects and advantages of the invention will appear from the following description and the features of novelty will be set forth in the appended claims.

The invention will be described in greater detail with the aid of the accompanying drawings, wherein

Fig. 1 is an elevational view taken along the

line 1—1 of Fig. 2, and looking in the direction of the arrows;

Fig. 2 represents a central vertical section along the line 2—2 of Fig. 1;

Figs. 3 and 4 are views taken respectively along the lines 3—3 and 4—4 of Fig. 2;

Fig. 5 shows a horizontal section through the switch and is taken along the line 5—5 of Fig. 1;

Fig. 6 is a detail showing one form of toothed disc carrying the bridging member and the insulating plate to which it is secured;

Fig. 7 shows the reverse side of the insulating plate and the driving ratchet disc secured thereto;

Fig. 8 is a view of the driving pawl;

Fig. 9 is an enlarged view in perspective of the mounting member constructed in accordance with the invention;

Fig. 10 is a view of another embodiment of my invention showing the manner in which a plurality of similar units may be built up on the mounting member for the control of additional circuits, the switch being designed for the control of two timed circuits or groups of circuits and of one group of non-timed circuits;

Fig. 11 is a view of still another form of my invention, and is a view taken along the line 11—11 of Fig. 12, the same being built up of similar units for the control of ordinary, non-timed circuits;

Fig. 12 represents a section along the plane represented by line 12—12 of Fig. 11; while

Figs. 13, 14 and 15 show details of the bridging and driving members.

Referring to the embodiment of the invention shown in Figs. 1 to 8, which is designed more particularly for the control of the circuits of a fluorescent lamp, referred to hereinabove, although suitable for any combination of timed and non-timed circuits, it will be seen that the housing is formed of two members 20 and 21 of similar construction and made of any suitable insulating material, such as a resinous moulding composition or of porcelain or the like. The housing sections 20 and 21 are secured upon opposite sides of a mounting member 22, which may be made of metal, such member being shown in detail in Fig. 9. This mounting member has a main portion of more or less U-shape composed of the central plate 22a and the legs 22b. Extending in opposite directions from the legs 22b are pairs of ears 23, 24 which are provided with threaded openings 25 for a purpose shortly to be described. A bearing plate 26 extends from the main plate 22a, more or less in the same plane as a pair of opposite ears 23, 24, and is apertured as shown at 27 for the reception of the driving shaft 30. A threaded nipple 28 is secured to the plate 22a, the latter having an opening registering with the hollow interior of the nipple.

Referring to Fig. 2, it will be seen that the housing sections 20 and 21 are secured to the mounting member 22 by way of screws 29 which pass through suitable bores in the housing sections and are received within the threaded openings 25. There is thus provided a compact and neat construction in which either of the housings and its associated mechanism, described below, can be removed and either such mechanism, or both the housing and the mechanism replaced with a unit having different switch characteristics.

The driving shaft 30 is mounted for oscillating movement within the central openings in the housing members 20 and 21 and passes through

the opening 27 of the bearing plate 26. As can be seen best from Figs. 2 and 5, the housing members are centrally hollowed out to provide chambers 31 and 32 within which the contact mechanisms are housed. As already indicated, the shaft 30 is designed to be oscillated through a limited arc, and in the form of the invention illustrated in these figures, the contact mechanism located in the chamber 32 is so constructed and arranged that during one complete oscillation of the shaft, the circuits controlled by the contacts in such chamber are both made and broken; while the contacts arranged in the chamber 31 are so disposed and operated that successive complete oscillations are required to effect closing and opening of the circuits in alternation.

The housing section 21 (Fig. 1) is provided on its outer face with two pairs of more or less radial slots 33 running from the periphery of the housing inwardly to communicate with the chamber 32, the slots being arranged at 90° intervals, as illustrated. The slots are designed to receive the conductors 34, 34 and 35, 35 which are introduced thereinto from the right as viewed in Fig. 2. To the opposite pairs of conductors 34, 34 and 35, 35, there are soldered or otherwise secured, the spring contacts 34a, 34a and 35a, 35a. The spring contacts may be made of phosphor bronze or any other resilient material and are generally of Z-shape, one end being anchored within lateral recesses 36 communicating with the slots 33. The free ends 36a of the spring contacts project into the chamber 32.

The shaft 30 is of non-circular cross-section, preferably square, except for the portion journaled in the housing section 20, which may be round. Mounted upon the shaft and within the chamber 32 is a bridging member which includes a disc member 37 made of suitable insulating material, such as porcelain, glass, resin, or fiber board. The bridging member is provided with a non-circular opening so as to fit snugly over the end of the shaft and rotate therewith. It is provided upon its peripheral surfaces with four arculate sections eccentric with respect to the center of the shaft, thereby forming four cam surfaces or teeth, there being more or less radially extending shoulders 38 between the successive cam surfaces. As can be seen from Fig. 1, the disc 37 and the spring contacts 36 are so disposed that the free ends of the latter ride smoothly over the cam surfaces as the member 37 is oscillated in the clockwise direction and then returned.

The bridge member 37 carries two identical bridging conductors 39 and 40 which are securely mounted thereon, each being composed of an annular section 41 whose central opening clears the shaft 30. The conductors are provided with diagonally opposite terminal portions 42 overlying the peripheral cam surfaces of the bridge member 37 and extending in opposite directions. It will be understood that the member 39 is mounted upon one side of the member 37 while the member 40 is positioned upon the opposite side of each member, the terminals on the members 39 and 40 being displaced by 90°.

As shown in Fig. 1, the oscillating terminals 42 project beyond the shoulders 38 and overlie to a certain extent the adjacent cam surface. This projection insures maintenance of contact with the terminals 36a even in the case of excessive rotation of the shaft and also prevents accidental dropping of any terminal onto the next cam surface or tooth. The terminals 42 cover only about

one-half the peripheral length of each of such cam surfaces, the latter being suitably recessed to receive such terminals and to provide a smooth juncture between the terminal-covered portions of the cam surfaces and the uncovered, non-conducting portions of such surfaces.

The conductors 34, 34 and 35, 35 are connected to the heating electrodes of different fluorescent lamps and it will be seen that upon rotation of the shaft 30 through an angle of about 60 to 90°, the opposite pairs of terminals 36a will be bridged by the respective members 39 and 40, whereby the circuits to the heating coils of the respective lamps will be closed, and such circuits will remain closed so long as the shaft is held in its extreme position of movement. When the lamp has begun to burn steadily, manual release of the switch will cause return of the shaft to the inoperative position shown in Fig. 1 (by a mechanism about to be described), whereby the starting circuits will be broken. The lamps will then be operated by the circuits controlled by the switch mechanism within the housing 20.

Mounted upon the shaft 30 adjacent to the journalled end 30a is a bridging member composed of an insulating plate 43 having upon one side thereof a driving ratchet wheel 44, whose function will be described below, and upon the opposite side a toothed wheel 45 made of any suitable insulating material. The elements 44 and 45 are secured to the disc 43 in any suitable manner, as by means of tongues 46 struck from the body of the ratchet wheel 44 and passing through suitable openings in the disc 43 and into the openings 47 in the wheel 45. These parts are all provided with a circular central opening so that they are free to rotate upon and relatively to the shaft 30.

The toothed wheel 45 is provided with cam teeth 48. A conducting metallic bridge 49 is secured to the outer face of the wheel 45 and is provided with diametrically opposite contact surfaces 50 which are bent over to cover a pair of opposite teeth, the other pair of teeth being uncovered and thus presenting an insulating surface. As can be seen from Fig. 2, the wheel 45 is located within the chamber 31 of the housing 20. An annular insulating washer 51 is located between the housing 20 and the opposite ears 23, 24 of the mounting member 22, and in the illustrated construction the insulated disc 43 is in substantial alignment with the washer 51 with only a slight clearance therebetween, so that the switch mechanism of which the bridge member 49 forms a part is effectively closed against and insulated from the driving mechanism described hereinafter.

The housing 20 is provided upon its raised annular surface with two pairs of oppositely disposed slots 52 (Fig. 4), similar in construction and arrangement to the slots 33 shown in Fig. 1. The slots are adapted to receive conductors 53 which are connected to spring terminals 54. While only one pair of conductors 53 is shown in Fig. 4, it will be obvious that a second circuit can be controlled by a second pair of conductors located within the other pair of slots 52, except that the two circuits will be controlled in alternation; that is, when one is closed the other will be open. It will be seen that the washer 51 serves to close the slots 52 and thereby retain the conductors in place and at the same time insulate the metal contacts against the metal mounting member 22. The slots 33 of the housing 21 are similarly closed by an insulating plate 55.

The ratchet wheel 44 constitutes part of the actuating mechanism for the switch and is arranged to be operated by an oscillating member 57 which is actuated by a pull-chain 56 of conventional construction. To this end, the oscillating member 57 is provided with diametrically opposite dogs or pawls 58 which engage within openings 59 spaced 90° apart in the ratchet wheel 44. The member 57 is provided with a non-circular central opening 60 so as to be locked to and thereby rotate with the shaft 30; in other words, the pawl member oscillates through a more or less fixed angle with the shaft. In the position of rest, the pawls 58 are located within a pair of opposed openings 59; and upon actuation of the pull-chain, the pawls engage the forward wall of each recess and rotate the ratchet wheel 44 and parts 43 and 45 connected thereto through an angle of 90°.

The oscillating member 57 is provided with a flange 61 which extends first axially to provide a supporting surface for the pull-chain 56 and then extends radially so as to retain the chain between itself and the ratchet wheel 44. The rear-end portion of the flange is provided with a hook member 62 having an open slot 63 which serves for anchoring the chain, the ball at the end of the chain being positioned to rest against the shoulder 64 of the hook member 62, the connecting flexible wire of the chain passing through the slot 63, and the chain then being passed over the member 57 and within the flange 61. Any other suitable mode of mounting can of course be employed. The flange is interrupted as indicated at 65 to facilitate formation of the pawl 58.

A return spring 66 surrounds the shaft 30 and is connected at one end to a lug 67 struck from the body of the bearing plate 26 of the mounting member 22 (Fig. 9), while its other end is connected to the V-shaped groove formed between one of the pawls 58 and an oppositely bent tongue 68 on the member 57. If it is desired to vary the tension of the spring, its other end may be connected to the lug 69 on the bearing plate 26.

The radius of the outer portion of the hook member 62 is greater than the distance between the center of the shaft and the edges 70 (Fig. 3) of the legs 22b of the mounted member. The hook member accordingly cooperates with the edges 70 to limit the movement of the shaft in both directions. The length of the legs 22b is so determined that the shaft is given a total angular movement of somewhat more than 90°, the excess over 90° being the free play of the switch.

The switch is shown in Fig. 3 in its unactuated condition in which the hook member 62 bears against edge 70 of the lower leg 22b.

The parts may be assembled in the following manner: The shaft 30 is passed through the aperture of the bearing plate 26 of the mounting member 22 and through the central opening of the housing 21, and the toothed wheel 37 is then positioned upon the free end of the shaft. After placing the cover plate 55 upon the outer face of the housing 21, the latter is secured to the opposite ears 23 and 24 of the mounting member by means of the screws 29. These parts are now firmly connected with each other and the partial assembly can be easily handled without danger of displacement of any parts.

The spring 66 is now threaded upon the shaft and one end thereof is engaged with the lug 67 or 69. The oscillating member 57 with the pull-chain anchored thereon is now slid upon the shaft in such angular position that the hook member

62 is located externally of the edges 70. Upon engaging the free end of the spring 66 within the V-shaped recess between the tongue 68 and the adjacent pawl 58, the member 57 will be urged by the spring into the position shown in Fig. 3. It will be understood that the pull-chain has been passed through the hollow nipple 28. The assembly composed of the disc 43, ratchet wheel 44 and toothed wheel 45 is now positioned upon the shaft, and the washer 51 is arranged with its apertures in alignment with those in the adjacent ears 23 and 24. The housing 20 is now mounted upon the reduced free end 30a of the shaft 30, and upon insertion and tightening of the screws 29, the whole mechanism is united into a rigid and compact assembly. It will be understood that the conductors 35 and 53 are properly positioned within their respective housings 21 and 20 prior to assembly of the switch, and that the wheels 37 and 45 are properly positioned with reference to the cooperating contacts to provide the desired sequence of circuit closing and opening. The switch can be mounted in any suitable manner and may, for example, be secured to a support 71 which is clamped between a threaded washer 72 and a nut 73, the latter having a trumpet-shaped central opening through which the chain passes.

The operation of the above-described mechanism is as follows:

As has already been indicated, the oscillating actuating member 57 is, in effect, locked to and rigid with the shaft 30 and the same is true of the toothed wheel 37. The bridging assembly within the housing 20, however, composed of the parts 43, 44, 45 and 49, is free to rotate upon the shaft. Upon actuation of the pull-chain, therefore, the mechanisms within the housings 21 and 20 will rotate with the shaft, the ratchet wheel 44 being driven by the pawls 58 of the member 57. During this movement, the free ends 36a of the contact members within the housing 21 will ride upon the surfaces of the teeth until they engage the conducting members 42. This will close the circuits in which the contact members are connected. Where these circuits are connected, for example, to fluorescent lamps, the operator will hold the chain in its extreme position of movement until the lamps have begun to burn without flickering. He will thereupon release the pull-chain and the parts will be brought by the spring 66 into the position shown in Figs. 1 and 3. During this return movement, the toothed wheel 37 is returned with the shaft to its original position in which contact members 36a engage the insulating surfaces of the wheel. The auxiliary or starting circuits for the lamps are now broken, the making and breaking of these circuits thus occurring during a single actuation of the chain. The disc 43, however, does not return with the shaft but remains in its shifted position, the pawls 58 riding out of the openings 59 and passing in reverse direction into the next pair of diametrically disposed openings 59. The friction between the disc 43 and the shaft, coupled with the friction between the contacts 54 and the wheel 45 is sufficient to prevent rearward slipping of the disc 43 as the pawls 58 pass over the ratchet wheel 44 to their original position. Where necessary, a holding pawl or a friction element may be provided to insure against return of the wheel 43 although I have found in certain commercial devices constructed by me that this is not necessary. It will thus be seen

that the disc 43 and the parts attached thereto will be rotated step-wise in the same direction upon repeated actuation of the chain 56. When, therefore, the starting circuits of the fluorescent lamps are broken upon release of the chain 56, the contacts 54 remain in engagement with the contact surfaces 50 of the bridge member 49, so that the main operating circuits for the lamps remain closed. Upon the next actuation of the chain, these operating circuits will be broken, as will be readily understood.

It will be seen from the foregoing that according to the present invention there is provided an extremely compact switch construction in which the actuating mechanism is positioned within a mounting member, which at the same time provides the stops (edges 70) for limiting the movement of the actuating mechanism in opposite directions, and is constructed for connection in a convenient manner with separate switch housings whose switch mechanisms may each comprise a plurality of circuits which are opened and closed according to different plans. The parts are few in number and can be easily manufactured by stamping or molding. The different switch mechanisms are completely insulated from each other and from the actuating device so that the danger of short circuiting is eliminated.

30 The mounting member 22 itself serves also as an effective cover for the actuating mechanism housed within it, as it subtends more than 180° of the periphery of the switch. The exposed portion of the central section of the switch may 35 be closed by means of a sheet metal plate 74 provided with curved ends which fit about the stems of the screws 29. The plate is placed in position during the assembly of the switch prior to the insertion of the screws through the housing 21 and is held in position with the aid of its hooked end portions 75.

The housings are preferably provided with flat faces 76 for convenience in mounting. The metallic cover plate 74 may be provided with a widened central portion 77 (Fig. 5) which engages and overlaps the rear surfaces 76.

In the embodiment of the invention illustrated in Fig. 10, parts similar to those heretofore described are similarly numbered. The construction shown in this figure is, in fact, identical with that shown in Fig. 2, except that the shaft 30 has been extended through the cover plate 55 in order to receive a second toothed wheel 37 which is housed in a second housing 21. The arrangement of the contacts and their sequence of operation in this construction may be the same as or different from those described in connection with Figs. 1 to 8. Fig. 10 illustrates the ease with which the switch construction of the present invention lends itself to the addition of further switch units of more or less standardized construction for the operation of additional circuits of the same or different characteristics from those controlled by the switch mechanism within the housings immediately attached to the mounting member 22. It will be noted that all these switch mechanisms are actuated from one and the same operating device housed within the mounting member 22. It is believed that the construction and operation of the mechanism shown in Fig. 10 will be obvious from the detailed description hereinabove.

Figs. 11 to 15 illustrate a construction in which all the bridging members move step by step in the same direction upon operation of the actu-

ating mechanism. The structure in effect involves the use of a disc 43 and associated parts as shown in Figs. 6 and 7 with the difference that the central aperture of the disc is non-circular so that the disc is locked to the shaft and rotates therewith. The actuating mechanism, on the other hand, and particularly the member 57a which carries the pawls 58 is free to move relatively to the shaft 30 and to this end is provided with a circular central opening 60a in contrast to the non-circular opening of the member illustrated in Fig. 8. The operation of this form of invention will be clear from the foregoing, it being plain that the member 57a oscillates within a limited angle of movement while the shaft and the disc 43 mounted thereon move progressively in the same direction so that the connection between the contacts 54 is closed through the bridge member 49 during one actuation of the switch, and becomes broken on the next actuation thereof.

It will be apparent that any convenient number of housings 20 or 21 may be assembled upon a single mounting member 22 with the aid of screws 29 of appropriate length, and that any type of circuits can be controlled by the switch. Thus the various circuit combinations described in the patent to Popp, No. 2,158,084 and likewise other combinations, can be incorporated in the mechanism described hereinabove. The mechanism above described is equally well adapted for use in 2-way, 3-way, and 4-way switches. Any standard type of switch can be associated with the manually controlled time switch above described, as will be evident to those skilled in the art. Also it is not essential that the various discs or toothed wheels be arranged with their teeth "in phase"; on the contrary, one disc can be advanced with respect to the other or others, and the discs may have different numbers of teeth cooperating with different numbers of terminals within the separate individual housings or within a common housing.

While the actuating mechanism has been illustrated by way of example as being constituted of a pull-chain mechanism, it is obvious that other known devices for oscillating or continuously rotating the shaft can be used; thus, a hand operated knob could be mounted upon an extended end of the shaft, or a push-button could be employed with an off-center pawl, which reciprocates under the action of the finger of the operator and of a return spring and which engages a ratchet wheel associated with the shaft.

As already indicated, the edges 70 of the mounting member 22 may serve as stops for limiting the angular movement of the actuating pawl member. To this end the legs of the mounting member are made of such length with reference to the axis of the shaft passing through the member that the angular movement of the pawl member is limited to 90° plus a certain angle of play, which may be 30° or thereabouts.

It will also be clear that the shaft itself may either be arranged for oscillation or for stepwise rotation continuously in the same direction. The different bridge members will of course be so mounted on the shaft that the desired type or sequence of connection and disconnection is secured. Thus, where the shaft rotates stepwise in the same direction and the device is to include a manually controlled time switch, the toothed wheel for such time switch could be secured to the operating pawl and both such parts mounted to move freely on the shaft, that is, rotate rela-

tively thereto, the spring acting to return these parts to their initial position after actuation thereof.

It will be obvious that where my time switch is inserted within the short-circuiting line connecting the electrodes of a fluorescent lamp, such switch can be held closed until sputtering has ceased and the lamp is able to continue on its operating circuit upon opening of the short-circuiting switch. The illustrated mechanism can be easily adapted for the control of multiple filament bulbs, a plurality of motors, or a plurality of windings on the same motor, and in various other circuit combinations. The switch can be so mounted as to be completely concealed except for the nipple through which the pull-chain, or any other selected operating mechanism, passes.

It will be evident, finally, that by the use of the individual housing sections and the selection of suitable bridge members, various combinations of multiple switches operated from a single actuating means can readily be assembled with a relatively few standardized parts. Thus the same housings can be employed with bridge members whose contacts are connected in different ways; and also with bridge members which are mounted for continuous rotation in the same direction or for oscillation. As the assembly of the parts is both simple and rapid, the switch parts can be kept in stock in knocked-down condition and orders for any particular type of switch combinations can be quickly filled.

Various parts of the invention above described may be used without others without departing from the spirit or scope of the invention as defined in the appended claims. Thus my novel mounting member can be associated only with switch mechanisms operating in the conventional way, that is, with connection and disconnection only upon successive actuations of the switch; also, while the use of separate housing sections is desirable, the switch terminals and the bridge members may all be positioned within a common housing.

Certain features of the present invention not claimed herein are claimed in my continuation-in-part application, Serial No. 423,285, filed December 17, 1941.

I claim:

1. In an electric switch, a bridge member comprising a wheel made of insulating material and provided with a plurality of cam teeth upon its periphery, the cam surfaces increasing in radial dimension along their peripheral extension measured from the center of the wheel, and contact members upon only the portion of the cam surfaces of larger radius of at least certain of the teeth and projecting beyond such portions so as to overhang at least a portion of the adjacent insulating surface of smaller radius of the adjoining tooth, stationary contacts whose free ends are arranged to engage the insulating and conducting surfaces of said certain teeth in alternation, means for rotating said member through a limited angle smaller than the angle subtended by one of said certain teeth and the projecting portion of its contact member, and means for returning said bridge member to its initial position, each stationary contact thus playing permanently over the insulating and conducting surfaces of only one of the cam teeth of said member, and said projecting portions of the contact members insuring against dropping of a stationary contact onto the next tooth.

2. A bridge member for electric switches com-

prising a wheel made of insulating material and provided with a plurality of cam teeth upon its periphery, the cam surfaces increasing in radial dimension along their peripheral extension measured from the center of the wheel, and contact members upon only the portion of the cam surfaces of larger radius of at least certain of the teeth and projecting beyond such portions so as to overhang at least a portion of the adjacent insulating surface of smaller radius of the adjoining tooth, a conducting connection between the pair or pairs of contacts stationary contacts whose free ends are arranged to engage the insulating and conducting surfaces of said certain teeth in alternation, means for rotating said member through a limited angle smaller than the angle subtended by one of said certain teeth and the projecting portion of its contact member, and means for returning said bridge member to its initial position, each stationary contact thus playing permanently over the insulating and conducting surfaces of only one of the cam teeth of said member, and said projecting portions of the contact members insuring against dropping of a stationary contact onto the next tooth.

3. A bridge member for electric switches comprising a wheel made of insulating material and provided with a plurality of cam teeth upon its periphery which are eccentric with respect to the center of the wheel, there being an approximately 5 radially extending shoulder connecting the adjacent cam surfaces, and contact members upon only the portion of the cam surfaces of larger distance from the wheel center of certain of said teeth and projecting beyond the adjacent shoulders so as to overhang at least a portion of the adjacent insulating surface of smaller distance from the wheel center of the adjoining tooth, and a conducting connection between the pair or pairs of contacts, said bridge member being adapted 10 to be oscillated through an angle which is smaller than that subtended by a tooth with its overhang but which is greater than that subtended by the contact portion alone, whereby a cooperating stationary contact plays permanently over only a single tooth, makes and breaks contact during 15 each oscillation, and is prevented from falling onto the next tooth.
- 20

JOHN S. NUNES.
